PROCESS OF REFINING OIL

Benjamin Clayton, Houston, Tex., assignor to
Refining, Inc., Reno, Nev., a corporation of
Nevada

Application December 10, 1940, Serial No. 369,510

12 Claims. (CL 260—425)

This invention relates to a process of refining animal and vegetable oils, and more particularly to a process of removing residual impurities from such oil after it has been treated with alkali and the resultant soapstock separated from the oil.

In the processes of refining animal and vegetable oils by alkali treatment, the oil, after the resultant soapstock has been separated therefrom either by a settling or a centrifugal separation step, contains small amounts of residual alkali, soap and water. Even in oil separated from soapstock by means of a very efficient centrifugal separation such as that effected by means of a centrifuge having a large diameter bowl and inclined discs between which the light effluent is adapted to flow to render the separation more effective, it has been found that the oil thus separated may contain soap in the proportion of from 300 to 1500 parts per million. It is the practice now to wash this oil in separate equipment by the use of 10 to 20% of water and if the soap particles left in the oil after separating the soapstock are very difficult to remove, even a second washing operation may be employed. Present commercial practice favors a refined oil in which the soapstock has been reduced to from 10-12 parts per million. Following the washing step the oil is ordinarily subjected to a vacuum drying step to remove the last traces of water.

It has been found that relatively small quantities of water are ample to remove large quantities of soap if the water can be brought into sufficiently intimate contact with the oil in order for the water to reach a soap concentration which is in equilibrium with the concentration of soap remaining in the oil. It will be seen that if such a small quantity of water as 1% is added to an oil containing 1,000 parts per million of soap, there would be approximately ten times as much water as the soap in the oil. If all the soap were extracted in a single step the resulting soap solution would only have a soap concentration of about 10%. Therefore, by effecting intimate contact between the oil and the water it is possible to remove substantial quantities of the soap by means of a relatively small quantity of water.

The present invention contemplates the introduction of a small amount of wash water into the centrifugal bowl which is used for separating the oil from the soapstock or into the centrifuge which is being used for the first washing operation. In either event the water is brought into contact with the oil just after the oil has been separated from either the soapstock or the wash water, as the case may be. That is, the wash

water is introduced inside the neutral zone. The wash water thus extracts a considerable quantity of soap from the separated oil and then flows outwardly in the centrifugal bowl to join the heavy effluent composed of either soapstock or wash water. In this manner the centrifugal separation and one washing step can be accomplished in a single centrifuge, or two washing steps may be conducted simultaneously within a single centrifuge.

It is the principal object of the present invention to provide a method of washing refined oil in which small quantities of a washing liquid may be used to effect a substantial reduction in the impurities of the oil.

It is another object of the present invention to provide a method of introducing a small quantity of water into the oil in a centrifuge just after the oil has been separated from impurities.

It is a further object of the invention to provide a method of introducing wash water into the oil in a centrifuge just after the oil has been separated from a washing liquid.

Another object of the present invention is to provide a centrifuge which permits the introduction of a heavy washing liquid into a light effluent after the light effluent has been separated from the heavy effluent.

Other objects and advantages of the invention will appear in the following description of the process and apparatus shown in the drawing, in which

Fig. 1 represents a vertical section through a centrifugal bowl which may be used to carry out the present invention.

Fig. 2 represents a fragmentary vertical section of a modified centrifugal bowl; and

Fig. 3 represents a fragmentary plan section of the wash water inlet pipe.

The centrifuge in Fig. 1 is composed of a bowl 11 mounted on a shaft 12 and secured thereto by means of nut 13. The bottom of the bowl has an upwardly extending cylindrical portion 14 through which the shaft 12 passes. A sleeve 15 having perforations 16 therein is disposed around the cylindrical portion 14. The bottom of this sleeve rests upon the bottom of the bowl and the top of the sleeve is adapted to support a dished member 17 having an upstanding cylindrical portion 18 surrounding the sleeve 15. An inwardly extending flange 19 fastened to the top of the cylindrical portion 18 bears upon the top of the cylinder 15 and thus supports the dished member 17. The dished member follows the general contour of the bottom of the bowl and

is supported in spaced relation thereto by means of inwardly extending flange 20. Thus, there is a passageway extending from the inside of the cylindrical member 15, through the perforations 16, between the cylindrical members 15 and 18 5 and between the dished member 17 in the bottom of the bowl. Spaced near the periphery of the dished member 17 are pipes 21 which extend upwardly from the dished member and are fastened thereto to provide a flow communication with the space between the bottom of the bowl and the dished member. This pipe 21 is provided with suitable perforations 22 through which the wash water may be discharged into the main portion 10 of the bowl. The pipe 21 is preferably closed at the end so that the wash water will have to pass through holes 22 rather than directly out the end of the pipe. These pipes are preferably disposed inside the neutral zone of the bowl, that is, inside the interface between the heavy and light 15 effluents.

Surrounding the cylindrical portion 18 of the dished member is a tubular member 23 which is flared out near the bottom of the bowl to provide a passageway between the dished member and the tubular member. The bottom of the tubular member 23 is disposed above the dished member 25 to provide a passage 23' beneath the tubular member. This is accomplished by supporting the tubular member by means of ribs 24 which rest 30 upon the flange 19 of the dished member. The tubular member is provided with a plurality of outwardly extending fins 25 which in turn are provided with shoulders 26. A plurality of discs 27 are adapted to be slid over the tubular member and are provided with slots adapted to engage the shoulders 26 of the ribs 25, so that the discs will rotate with the tubular member. These discs may be of the conventional type employed in this type 35 of centrifuge, in which case they would be provided with perforations 28. By suitably constructing the dished member 17 and the water pipe 21 the perforations in the disc may pass over and surround the water pipes. In this case it is preferred to have the perforations 28 of sufficient size so that after the discs are disposed over the water pipe there will still be sufficient room between the outside of the pipe and the adjacent disc to allow the passage of heavy effluent along the outside of the water pipe. In this manner the advantages obtained by means of the perforated discs are not lost by the use of these perforations to provide a space for the water pipe. Where the perforations in the disc are not necessary for efficient separation it is apparent that the water pipe may be of sufficient size to occupy the entire space made by the perforations. The discs 27 are provided with the usual means of spacing so that the discs will be supported in spaced relation with each other. Above the last disc is disposed dam member 29 which has a downwardly extending flange 30 which is disposed to permit only heavy effluent to pass beyond it. At its upper end the dam member 29 has an upwardly extending flange 31 to which is attached the light effluent discharge tube 32. This tube has inwardly extending ribs 33 which engage the annular rib 34 of the tubular member 23 to hold the tube 32 in spaced relation with the tubular member 23, thus providing a passage for the light effluent. The discs and the dam member 29 are held together by means of the spider member 35 which in turn is held in position by the closure member 36. The lock ring 37 serves to hold the entire assembly together. A ring dam 38 sup-

ported by a shoulder on the inner surface of the closure 36 is held in position by the nut 39. This ring dam serves to determine the neutral zone in the centrifuge and may be replaced by another of different size when it is desired to shift the neutral zone.

The feed mechanism is composed of a central feed tube 40 supported by cover 41. The feed tube is provided with a spiral 42 which serves to feed the mixture to be centrifuged against the inside wall of the tubular member 23 and from there it may pass through the space between the tubular member 23 and the tube 18 and out through passage 23'. The wash water inlet 43 is disposed within the feed tube and passes through the center of the feed spiral. It extends down a considerable distance into the centrifuge and passes through a hole in the flange 19. The cap 44 may be provided to cover the nut 13 on the end of the shaft 12.

In Fig. 2 I have illustrated a modification of the centrifuge in which the water pipe is disposed beyond the discs and inside the neutral zone. In this modification a support 45 between the inside of the bowl and the top of the water pipe may be provided since in this case the discs do not surround the water pipe and accordingly the water pipe cannot be supported by them.

Fig. 3 shows a modification of the present invention in which the perforations in the discs are of an elongated shape. The short dimension of the elongated perforation is disposed along a radius. The water pipe is brought in contact with the sides of the elongated perforation and in this manner the discs serve to support the water pipe. The space provided by the elongated perforation permits the passage of the heavy effluent alongside of the water pipe.

In operation the oil containing the soapstock 40 to be separated therefrom is conducted into the feed pipe 40, is forced to the periphery of the feed pipe by means of the spiral 42 at the end of which it is discharged against the inner wall of the tubular member 23 and flows downwardly through the space between this tubular member and the tube 18 and is distributed toward the periphery of the centrifuge bowl by means of the outwardly flared portion of the tube 23. The soapstock is thrown against the inside of the bowl while the oil is forced inwardly to pass between the discs 27. The wash water is introduced through the pipe 43, passes through the perforations 16, the space between the tubes 15 and 18 and into the water pipe 21 from which it is distributed through the holes 22. This water flows countercurrent to the inward flow of the oil and effects intimate contact with the oil, thus removing a substantial portion of the soapstock and other impurities from the oil. Some of the 55 wash water containing the soapstock and the impurities may discharge through the perforations 28 and the discs and thus take a short path to the heavy effluent discharge. Other portions of the wash water pass outwardly between the discs and join the main portion of the soapstock which is withdrawn at the heavy effluent discharge. The oil after passing the stream of wash water flows inwardly along the surface of the discs and is discharged into the space between the 60 ribs 25 and from there it flows upwardly through the space between the tubes 32 and 23 and is discharged through the light effluent discharge. The heavy effluent along the inner wall of the bowl passes around the flange 30 of dam member 29, up through the space between members 65

29 and 38, over the ring dam 38 and out the heavy effluent discharge.

It will be apparent that by means of the present process a single centrifuge may be used to effect the primary separation of impurities from the oil as well as to effect a substantial washing of the separated oil.

The washing accomplished by this small amount of water either makes a separate washing unnecessary or, in the case of oil from the primary separation containing an excessive amount of light floating soap, only one separate operation may be required.

The present process may also be employed to effect a double washing within a single centrifuge. Thus, a refined oil from which the majority of the soapstock has been separated but which contains from 300 to 1500 parts per million of soap can be admixed with a considerable quantity of water, which mixture can be separated in the present centrifuge. This washing will remove up to 95% of the residual soapstock and by the use of additional wash water discharged into the separated washed oil it is possible to reduce the residual soapstock content to within commercial limits.

The quantity of wash liquid employed may vary with the different oils as well as with different batches of the same type of oil. In some cases wash water in the amount of 1% of the oil treated has been found effective. In others 2 or 3% may be more effective. Likewise, less than 1% may be found satisfactory in particular instances.

In the treatment of certain oils it may be desirable to heat the material in the centrifuge. This may be done in the manner disclosed in my Patent No. 2,100,277. Likewise, heat may be added by the use of hot water, even above its atmospheric boiling point if pressure is employed.

The present process is not limited to the removal of residual soapstock from a refined oil but may also be employed to wash any impurities from the oil after it has been subjected to any kind of refining treatment. For example, where the oil is subjected to a degumming treatment the present process may be employed to remove traces of gums and other impurities which have precipitated but which have remained with the oil and have not been separated in the primary separation. Likewise, it can be employed to remove residual traces of impurities as well as acid from an oil which has been subjected to acid refining.

Similarly, the present process while preferably employed in conjunction with the continuous refining of oil, such as according to U. S. Patent No. 2,100,274, is not limited to continuous refining but may also be employed to remove residual impurities from oil refined according to the batch process.

The various modifications of the process of the present invention are applicable to vegetable and animal oils in general. Such vegetable oils as cottonseed oil, corn oil, soya bean oil, linseed oil, sesame oil, etc. are within the contemplation of the invention. The term "animal oils" is also intended to include fish oils, such as sardine, menhaden, or herring oils. By the employment of the terms "oils" or "oil" in the claims I intend to embrace glyceride fats or oils, irrespective of the viscosity thereof.

While the description of the present invention has been particularly directed to the use of the type of centrifuge illustrated, it will be apparent

that other types of centrifuge may be modified to perform the present invention.

It is apparent that other washing liquids besides water may be used if desired. For example, various electrolytes may be employed particularly where the process is employed for the removal of gums and phosphatides. Likewise, in certain instances, soap solvents such as alcohols which are immiscible with the oil may be employed, either alone or in admixture with other liquids such as water.

While various modifications have been disclosed the invention is not to be limited thereto but it is to be understood that it may be varied within the scope of the appended claims.

What I claim is:

1. The process of separating impurities from glyceride oil which comprises subjecting said oil containing impurities to centrifugal separation in a centrifuge to remove a portion of the impurities therefrom, washing the resultant separated oil by introducing a relatively small quantity of washing liquid into said separated oil within said centrifuge immediately following separation.

2. The process of separating impurities from glyceride oil which comprises subjecting said oil containing impurities to centrifugal separation in a centrifuge to remove a portion of the impurities therefrom, and washing the resultant separated oil by introducing a relatively small quantity of washing liquid into the separated oil inside the neutral zone of said centrifuge while said separation is being affected therein.

3. The process of separating impurities from glyceride oil which comprises subjecting said oil containing impurities to centrifugal separation in a centrifuge to remove a portion of the impurities therefrom, introducing a relatively small quantity of a washing liquid into the resultant separated oil while said oil is still within said centrifuge, and removing the washing liquid along with the previously separated impurities.

4. The process of separating soapstock from glyceride oil which comprises subjecting said oil containing soapstock to centrifugal separation in a centrifuge to remove a portion of the soapstock therefrom, introducing into the resultant separated oil while in said centrifuge a relatively small quantity of a washing liquid, and separating the washing liquid from the oil.

5. The process of separating soapstock from glyceride oil which comprises subjecting said oil containing soapstock to centrifugal separation in a centrifuge to remove a portion of the soapstock therefrom, introducing into the resultant separated oil while in said centrifuge a relatively small quantity of water, and separating water from the oil.

6. The process of separating impurities from glyceride oil which comprises subjecting said oil containing impurities to centrifugal separation to remove a portion of the impurities therefrom, admixing the resultant separated oil with a quantity of washing liquid and subjecting the mixture to centrifugal separation, introducing into the resultant washed oil while in the centrifuge used for said last mentioned separation and immediately following separation from the washing liquid a relatively small quantity of washing liquid, and separating the washing liquid from the oil.

7. The process of separating soapstock from glyceride oil which comprises separating the major portion of the soapstock from the oil, admixing the separated oil with a quantity of wash-

ing liquid, subjecting the mixture to centrifugal separation in a centrifuge to remove a portion of the washing liquid and residual soapstock therefrom, introducing into the resultant separated oil while in said centrifuge a relatively small quantity of washing liquid, and separating the washing liquid from the oil.

8. The method of refining glyceride oil which comprises treating the oil with an alkaline refining agent, separating the major portion of the resultant soapstock therefrom, admixing the resultant separated oil with a quantity of washing liquid, subjecting the mixture to centrifugal separation in a centrifuge, and introducing into the separated oil while in said centrifuge a relatively small quantity of washing liquid to remove residual impurities from the oil.

9. The process of separating soapstock from glyceride oil which comprises subjecting a mixture of oil and washing liquid to centrifugal separation in a centrifuge to remove a portion of the residual soapstock therefrom, introducing into the resultant separated oil while in said centrifuge a relatively small quantity of washing liquid, and removing the washing liquid from the oil.

10. The process of separating impurities from glyceride oil which comprises subjecting said oil containing impurities to centrifugal separation in a centrifuge to remove a portion of the impurities

therefrom, introducing a relatively small quantity of a washing liquid into the resultant separated oil within said centrifuge, removing the washing liquid along with the previously separated impurities and heating the bowl of the centrifuge during said separation to a relatively high temperature so as to lower the viscosity of the oil.

11. The process of separating impurities from a glyceride oil which comprises introducing an oil containing impurities into a centrifuge, forming a layer of impurities and a layer of separated oil, said layers being separated by a neutral zone, introducing into said separated oil layer a small quantity of a washing liquid, forcing said washing liquid through at least a portion of said separated oil, through said neutral zone and into said layer of impurities, and separately removing impurities and oil from said centrifuge.

12. The process of separating impurities from a glyceride oil, which comprises, subjecting said oil containing said impurities to centrifugal force in a centrifuge to separate said impurities from said oil, introducing a washing liquid into said oil while the same is still passing through said centrifuge and after a portion of said impurities has been separated from said oil, and separating washing liquid from said oil in said centrifuge to remove additional impurities therefrom.

BENJAMIN CLAYTON.
